UNITED STATES PATENT OFFICE.

WILLIAM ALEXANDER ROSEBERRY AND PAUL S. JUNKIN, OF CRESTON, IOWA.

LINER FOR MOLDS FOR LINOTYPE-MACHINES.

No. 892,685.

Specification of Letters Patent. Patented July 7, 1908.

Application filed February 18, 1907, Serial No. 358,132. Renewed March 11, 1908. Serial No. 420 352.

To all whom it may concern:

Be it known that we, WILLIAM ALEXANDER ROSEBERRY and PAUL S. JUNKIN, citizens of the United States, residing at Creston, in the county of Union and State of Iowa, have invented certain new and useful Improvements in Liners for Molds for Linotype-Machines; and we do hereby declare the following to be a full, clear, and exact description of the invention, such as will enable others skilled in the art to which it appertains to make and use the same.

This invention relates to a novel construction in a liner for linotype machines and has for its object to provide simple and efficient means whereby a hollow or recessed type-bar or slug may be cast in the mold of the character employed for casting solid rectangular type-bars or slugs, and consists in the features of construction and combinations of parts hereinafter fully described and claimed.

In the accompanying drawings illustrating our invention: Figure 1 is a plan view of a mold for linotype machines provided with means constructed in accordance with our invention for casting a hollow or recessed type-bar therein, the latter and the liners being shown in section on the line 1—1 of Fig. 2. Fig. 2 is a view in side elevation of the liners removed from the mold and showing the type-bar or slug therein in dotted lines. Fig. 3 is a view of the opposite side of the liners from that shown in Fig. 2, the type-bar or slug being removed. Fig. 4 is a perspective view of the type-bar or slug.

It is desirable in casting slugs to reduce the weight thereof not only to reduce transportation charges but likewise to enable a larger number of slugs to be produced from a given quantity of metal, thus reducing the investment in the latter.

The molds usually provided are adapted only to cast solid rectangular type-bars or slugs of any desired length or width of column, while for the casting of hollow slugs special and very expensive molds are necessary.

The primary object of our invention is to provide means whereby the mold ordinarily employed for casting solid slugs may be converted into a mold for casting hollow slugs, by using our liners whereby a single mold will answer all purposes of the linotype maker or operator.

To this end the invention consists in providing each of the liners A and B, disposed

between the members C and D of the mold and which determine the length and width of the mold cavity, with a projection E at its inner end which is of substantially one-half the thickness of the liner and one face of which is flush with one face of said liner so that said projection will lie snugly against one wall of the mold cavity. Said projection E of each liner is of less height than said liner and the lower face thereof is flush with the lower face of the liner. The free end of said projection is also slightly inclined so that said projection is of greater length on its lower than on its upper face or edge. Each of said projections is further provided adjacent its juncture with the body of the liner with a recess F one wall of which is flush with the inner end wall of said liner, and which extends from the upper edge or face of said projection to a depth of about two thirds three-quarters the height thereof, said recesses being slightly flaring toward their mouths. The combined length of said projections E is less than the length of the mold cavity so that between the opposing free ends of said projections a substantially V-shaped recess G is formed. Said liners A and B are each provided on one face with a rib H which is adapted to enter a groove I in the face of the member C of the mold and said liners thus held against lateral movement with relation to the said mold members.

As in the case of ordinary molds a number of sets of liners must be had in order to produce mold cavities of various sizes to accord with the different widths of column and size or point of type to be cast and also to properly position such cavity between the ends of the mold. Hence, in order to cast hollow slugs it will be necessary for the operator to provide himself with liners constructed in accordance with our invention, in addition to the liners he employs for casting solid slugs.

In casting the slug the metal flows into the recesses F and G as well as filling the remainder of the mold cavity, thus forming the slug J provided in one of its side faces below the type-face with recesses K bordered at their ends by the ribs L and M. A sufficient thickness of metal is provided over said recesses K to withstand the pressure to which the type is subjected.

The ribs H of the liners A and B serve to hold said liners against lateral movement relatively to the mold members, and to hold the same against vertical movement with rela-

tion thereto we provide projections N on the liners which are adapted to enter recess O in the mold cap.

The employment of liners made in accordance with this invention also necessitates the employment of an ejector blade which engages only the lower face of the slug cast and which will readily pass through the reduced mold cavity. Illustration and description of such ejector blade or ejecting means is omitted as being superfluous and forming no part of our present invention.

We claim as our invention:

1. In a mold for linotype machines, the liners provided at their inner ends with projections partially filling the mold cavity at one side thereof, said projections having flaring recesses therein, the mouths of said recesses being in the upper edges of said projections.

2. In a mold for linotype machines, the liners provided at their inner ends with projections partially filling the mold cavity at one side thereof, the free ends of said projections being inclined to provide a substantially V-shaped recess between the same.

3. In a mold for linotype machines, the liners provided at their inner ends with projections partially filling the mold cavity at one side thereof, the free ends of said projections being inclined to provide a substantially V-shaped recess between the same, there being recesses in said projections extending downwardly from the upper edges thereof.

4. In a mold for linotype machines, the liners constituting the end walls of the mold cavity, a projection carried by each of said liners and partially filling the mold cavity at one side thereof, the upper edges of said projections being disposed below the upper end of said mold cavity and provided with recesses in their upper edges.

In testimony whereof we have signed our name in presence of two subscribing witnesses.

WILLIAM ALEXANDER ROSEBERRY.
PAUL S. JUNKIN.
